JOURNAL BOXES

Robert Steinmann, Jersey City, N. J., assignor to General Motors Corporation, Detroit, Mich., a corporation of Delaware

Application August 30, 1954, Serial No. 452,866

5 Claims. (Cl. 308—41)

This invention relates to journal boxes and more particularly to a cushioning arrangement in a journal box for resiliently receiving and absorbing the endwise thrusts of a rotatable axle on a railway car.

An object of this invention is to provide a journal box having an improved thrust receiving arrangement for resiliently cushioning and limiting the axial movements of an axle rotatable in the journal box.

Another object is to provide a journal box having an improved thrust receiving arrangement of simple and economical construction which may be quickly and easily installed in and removed as a unit from the journal box and which will resiliently cushion end thrusts of an axle rotatably journaled in the box.

A further object is to provide in a thrust receiving arrangement for a railroad journal box a unit-handling demountable assembly which will resiliently cushion and limit the end thrusts of an axle.

To these ends and also to improve generally upon devices of this character, the invention consists in the various matters hereinafter described and claimed. In its broader aspects, the invention is not necessarily limited to the specific structures selected for illustrative purposes in the accompanying drawings wherein:

Figure 1 is a vertical cross section taken through the forward end of my journal box.

Figure 2 is a fragmentary horizontal section taken along the line 2—2 of Figure 1 and showing my thrust receiving arrangement under load.

Figure 3 is a fragmentary vertical section through the forward end of the journal box with the thrust absorbing mechanism removed.

An axle 10 is mounted for free rotation in a journal box 12 by a plurality of similar rows of bearing rollers 14 that roll upon a hardened inner raceway sleeve 16 pressed over an end of the axle 10 and upon the inner surface of a hardened outer raceway sleeve 18 pressed into the journal box. The axle 10 may also assume a limited endwise shifting movement within the rows of bearing rollers. A rotatable cage 20 is provided with peripherally spaced roller-receiving pockets to locate the rollers in circumferentially spaced relation. The rows of rollers are separated from each other endwise by an intermediate ring 22 journaled in the outer raceway sleeve 18 and radially spaced from the cage 20. Suitable lubricant such as oil is located within a well 24 to a sufficient level so that it has access to the rollers which distribute it to the various moving parts within the box.

A plug 25 in the box may be removed to facilitate filling of the well 24 to the proper level. A lubricator ring 28, surrounding the end of the axle in spaced relation, is slidably mounted in the forward end of the journal box between an inwardly extending abutment rib 29 and the forward end of the outer raceway sleeve 18. This ring 28 which is held from rotation as by a pin or screw in the box 12, has a hardened annular flange 31 which engages and guides the forward ends of the rollers 14. Oil picked up by the bearing rollers 14 is directed through a lateral

2

passage 34 through the top of the ring 28 and then by an inclined face 35 on this ring into a pan 36 projecting from an inclined cover 37 demountably held in position by screws and normally closing an opening 40 in the upper forward end of the box 12. A gasket between the cover 37 and the box prevents leakage of oil around the cover.

Lubricant is drained from the sloping bottom of the pan 36 through a hole 42 onto an inclined lip 44 formed on the top of a thrust block 45 from which the lubricant 10 is directed into a pocket 46 that connects with an eccentric lubricating groove 48 formed in the flat end of a facing member 50 engageable with the end of the axle 10. This facing member 50 which may be made of bronze or other material having a low coefficient of friction against the 15 axle in the presence of lubricant, is demountably secured as by rivets or other suitable means to the thrust block to provide for replacement of the facing member when it wears too thin for satisfactory service. A witness groove 52 is cut in the periphery of the facing member 20 50 so that the distance between the axle engaging face of the member 50 and this groove may be measured to determine the extent of facing member wear.

A tubular thrust block extension 54 projects towards but terminates in spaced relation to the forward end 25 wall 55 of the journal box 12. Coextensive axial bores 56 and 57 through the facing member 50 and the extension 54 reduce the weight of the thrust absorbing mechanism and aid lubrication and cooling. A pair of similar laterally extending arms 60 project in opposite directions from 30 the body portion of the thrust block adjacent to the facing member 50. Each of these arms 60 terminates in a forwardly extending foot 61 which is generally rectangular and is provided with an arcuate end face 62. Each foot is loosely received in a rectangular recess 63 having 35 top and bottom guiding walls 64 and 65 against which the foot may slidably engage, this recess being longer than the foot received therein to allow for endwise thrust block movements when the axle 10 moves endwise against the facing member 50. The forward movement of the 40 thrust block 45 is limited by engagement of the feet 61 respectively against forward end walls 66 of the recesses 63. Each rectangular recess 63 is formed in the inner end of a swivel bushing 68 journaled in a bore through the side of the journal box 12 and demountably secured 45 in position by a closure plate 70 that is detachably secured to the side of the box as by screws. Each swivel bushing has an annular flange 71 engageable against the bottom of a counterbore in the box to limit the innermost positions of the swivel bushings so that the feet 61 will not be cramped thereagainst but will be free to move 50 in the recesses 63. Pins 74 secured in and projecting through the forward end 55 of the box are loosely received in slots 75 in the bushings 68 to permit the required amount of swivel movement to these bushings so that 55 the thrust block 45 may tilt sufficiently about a horizontal axis transversely of the axle to assure flat faced engagement of the end of the axle against the facing member 50. The individual slidably interfit of the feet 61 in their respective recesses 63 allows for tilting of the 60 thrust block about a vertical axis to further assure flat faced engagement of the axle end against the facing member 50.

My thrust cushioning arrangement, as illustrated, includes a series of cooperating resilient washers 80 and a 65 thrust collar 82 loosely secured together as a unit-handling assembly and located between a flat annular shoulder 83 on the thrust block 45 and a flat boss 84 on the inside of the end box wall 55. These spring washers 80, which 70 may comprise a series of cooperating frusto-conical washers dished in opposing relation and commonly referred to as Belleville washers, together with the collar 82 are loosely slidably journaled in substantially non-

compressed relation on a sleeve 86 that is slidably and demountably fitted over the tubular extension 54, the ends of this sleeve being slightly upset or spun over to hold the washers 80 and thrust collar 82 in unit-handling assembled relation. The inner end of this sleeve enters an annular recess 87 in the thrust block and the sleeve is demountably secured in position on the tubular extension 54 by a snap ring 90 seated in a groove in the extension 54. An annular flange 92 terminating in a flat face projects from the body of the collar 82 and has pressed thereover in tightly fitting relation a flanged cap 94 normally engaging the boss 84. A series of annular shims 96 fitted between the cap 94 and the flange 92 are preferably assembled in such number and combined thickness that the Belleville washers 80 will initially be compressed under a slight predetermined preload between the flat shoulder 83 and a corresponding opposed flat face on the collar 82 thereby locating the forward ends of the thrust block feet 61 against the forward end walls 66 when the axle 10 is exerting no end thrust on the facing member 50. This arrangement simplifies assembly of the many parts of the cushioning mechanism as a unit which may be quickly and easily slid in place over the thrust block. Furthermore, with this arrangement, Belleville washers of required resiliency may be preassembled in the cushioning unit to provide cushion units which are especially adapted to absorb endwise axle thrusts dependent on a particular car and on the condition under which it will be used.

In operation, when a car equipped with my box encounters a straight even run of track, there is normally a slight spacing between the flat end of the axle and the adjacent flat end of the facing member 50. When negotiating rough portions of track or curves, the axle may shift endwise into facing member engagement. Further endwise shifting of the axle in this direction compresses the Belleville washers together as shown in Figure 2 thereby causing them to rapidly build up a resiliently cushioned resistance that yieldably absorbs the endwise axle thrust, this endwise axle movement being finally limited when the washers compress to a solid form at which time the thrust block 45 is solidly backed up by the Belleville washers, collar 82, shims 96, cap 94, and end box wall 55. When the axle 10 shifts endwise away from the facing member 50, the combined resilient action of the Belleville washers will again locate the thrust block against the forward recess walls 66 ready for the next thrust absorbing action.

I claim:

1. In a journal box having an axle journalled for rotation and shiftable endwise therein, a thrust block engageable with the end of the axle to receive endwise axle thrusts, thrust block projections supported at the sides of the box for slidable movement of the block endwise of the axle, a thrust block shoulder adjacent said projections, a thrust block extension projecting longitudinally of the axle into spaced relation with an end wall of the box, a unitary sleeve slidably journalled on the extension and located in spaced relation to said shoulder, a plurality of resilient dished washers slidably journalled for free axial movement on the sleeve and compressed between the thrust block shoulder and said end wall to urge the thrust block towards the axle, means on the sleeve loosely holding the washers and sleeve in unit-handling assembly, and means engageable with an end of the sleeve and securing the sleeve and washer assembly in demountable unit handling relation with the thrust block.

2. In a journal box having an axle journalled for rotation and shiftable endwise therein, a thrust block engageable with the end of the axle to yieldably receive and cushion endwise axle thrusts, lateral thrust block projections slidably supported by the box for thrust block movement endwise of the axle, a tubular thrust block extension projecting in a direction lengthwise of the

axle and terminating at one end in spaced relation to an end wall of the box, a thrust block shoulder at the other end of said extension, a sleeve slidably journalled on said extension and spaced from said shoulder, a collar slidably journalled on the sleeve and abutting said end wall, a plurality of resilient washers dished in opposing relation for axial compression between the collar and said shoulder and slidably journalled on the sleeve, end portions on the sleeve securing the washers and collar in loose unit-handling assembly, the washers cooperating to yieldably resist thrust block movement towards said end wall, and detachable means on the thrust block securing said unit-handling assembly in unit-handling assembled relation with the thrust block.

15 3. In a journal box having an axle journalled for rotation and shiftable endwise therein, a thrust block normally spaced from the end of the axle and engageable therewith to yieldably receive and cushion endwise axle thrusts, laterally extending arms on the thrust block, supporting members demountably received in the sides of the box, an end of each arm being slidably supported in one of the supporting members, a tubular extension on the thrust block projecting into spaced relation with an end wall of the box, a thrust block shoulder at an end of the tubular extension, a sleeve demountably and slidably journalled on the tubular extension, said sleeve being radially spaced from the thrust block shoulder, a plurality of inter-engaging resilient washers slidably journalled on and in unit-handling relation with the sleeve, one of said washers 20 engaging the thrust block shoulder, and said washers resiliently resisting thrust block movement transmitted thereto by endwise shifting of the axle.

25 4. In a journal box having an axle journalled for rotation and shiftable endwise therein, a thrust block normally spaced from the end of the axle and engageable therewith to yieldably cushion endwise axle thrusts, laterally extending arms on the thrust block, bushings demountably journalled in the sides of the box, each bushing having an elongated recess for slidably and tiltably receiving an end of an arm, means limiting the rotatable movement of the bushings, a thrust block shoulder adjacent the arms, a tubular thrust block extension projecting endwise of the axle from said shoulder into spaced relation with an end wall of the box, the thrust block 30 having an annular recess between said tubular extension and said shoulder, a sleeve slidably journalled on the tubular extension, said sleeve extending into said recess and located in spaced relation to said shoulder, a plurality of axially resilient washers slidably journalled on the sleeve, one of said washers engaging said shoulder, said washers cooperatively exerting a resiliently yieldable thrust against said shoulder, and upset end portions on the sleeve loosely securing the washers and sleeve in unit-handling relation.

35 5. In a journal box having an axle journalled for rotation and shiftable endwise therein, a thrust block normally spaced from the end of the axle and engageable therewith to yieldably cushion endwise axle movement, laterally extending arms on the thrust block, bushings demountably journalled in the sides of the box, each bushing having an elongated recess for slidably and tiltably receiving one of the arms, means limiting the rotatable movement of the bushings, a thrust block shoulder adjacent to said arms, a tubular thrust block extension of 40 uniform diameter projecting into spaced relation with an end wall of the box, the thrust block having an annular recess between the shoulder and said tubular extension, a sleeve slidably journalled on the tubular extension, a member detachably securing the sleeve in position, a collar slidably journalled on the sleeve and abutting said end wall, a plurality of axially resilient dished washers compressed between the collar and the shoulder and tending to yieldably hold the thrust block against one end of each of said recesses, upset end portions of the sleeve 45 loosely securing the washers and collar in unit-handling

assembly with the sleeve, and one of said end portions extending into said recess in spaced relation to said thrust block shoulder.
